CLAIM

The ornamental design for a foldable trolley, as shown and described.

DESCRIPTION

FIG. 1 is a front, left and top side perspective view of a foldable trolley showing my new design;

FIG. 2 is a rear, right and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view showing the folded state thereof;

FIG. 10 is a perspective view showing the folded state thereof; and,

FIG. 11 is an enlarged view of the portion marked '11' of FIG. 2.

The broken lines shown in the drawings represent portions of the foldable trolley that form no part of the claimed design.

The dot-dashed broken lines in FIG. 2 indicate cutoff boundaries for the enlarged detailed portion views and form no part of the claimed design.
